[57] CLAIM

The ornamental design for a reflective sheet unit for
archery bow limbs, as shown and described.

DESCRIPTION

FIG. 1 is a front elevational view of a Reflective Sheet
Unit for Archery Bow Limbs, showing my new design,
the rear is plain and unadorned, and claimed design is of
conventional thickness; and,

FIG. 2 is a front elevational view of a second embodiment
thereof.

The broken lines showing a bow limb are for illustrative
purposes only to illustrate the environment in which the
reflective sheets are used and form no part of the
claimed design.
